UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW JERSEY.

CAN-CLOSING MACHINE.

Application filed September 14, 1925. Serial No. 56,272.

My invention relates to can closing machines, and has for its object the provision of a double seamer adapted to close metal containers in which the seam is formed intermediate the ends of the container.

In the ordinary type of double seaming machine, a chuck is provided to enter a counter-sunk portion of the can end and back up a vertical wall formed just inwardly from the attaching flange, the can body and cover thus being held in proper relationship during the seaming operation. This seaming operation may be performed by either of two well-known types of seaming mechanism, one in which the container is held in fixed position and the seaming mechanism rotated thereabout, and the other in which the seaming mechanism is stationary and the can is rotated in contact with seaming rollers which are presented in proper timed relationship. The machine of my invention is of the latter type and differs from the ordinary seaming machine in that provision is made for attaching a cover which is not of the counter-sunk type but of such shape that the attaching flange is disposed beneath the top of the cover. The invention resides in the construction and combination of elements whereby the machine is adapted to this purpose.

Numerous other objects and advantages of the invention will be apparent as it is better understood from the following description, which, taken in connection with the accompanying drawings, discloses a preferred embodiment thereof.

Referring to the drawings,

Figure 1 is a front elevation of a seaming machine in which my invention is embodied, a can being shown in seaming position and parts thereof broken away to better illustrate the seaming mechanism;

Fig. 2 is a side elevation of said machine;

Fig. 3 is a plan view of the seaming roller carrier and the handle by which the same is moved to arrange the rollers in contact with the work;

Fig. 4 is an enlarged sectional view of the seaming mechanism, taken substantially on the section line 4-4 in Fig. 2;

Fig. 5 is a sectional detail of the first operation seaming roll; and

Figs. 6, 7 and 8 are enlarged sectional and elevational views showing the form of the can seam during the successive seaming op-

erations, said views illustrating, respectively, the first, second and third operation rollers.

A can of the type upon which the machine of my invention is adapted to operate is shown in Figs. 1 and 4 of the drawings. Said can comprises a cylindrical body 11, having a bottom end 12 and an upper end or cover 13, which has a central opening 14 in the top thereof adapted to be closed by means of a suitable friction plug closure (not shown). It is contemplated that the lower end, or bottom member 12 may be applied by means of another double seaming machine of my invention, which is disclosed and claimed in a co-pending application of even date herewith, bearing Serial No. 56,271. It will be observed that the container consisting of these parts is of drum shape and the seams by which the end members are attached to the body are disposed intermediate the ends of said container. The upper end or top member 13 is adapted to be applied by the machine of the present invention, which will now be described.

Referring first to Figs. 1 and 2 of the drawings, the reference character 15 indicates a standard or column, arising from a base 16 and having journaled in the upper part thereof a horizontal drive shaft 17, carrying a belt pulley 18 adapted to be driven from any suitable source of power. Said shaft carries at its inner end a bevel gear 19, meshing with a like gear 21 on a vertical shaft 22 journaled in bearings 23 and 24 formed in forward extensions 25 and 26 of the standard or column 15. Said shaft has a gear 27 secured to the lower end thereof and disposed within a housing 28 formed beneath the bearing 24, said gear meshing with an internal gear ring 29 mounted for rotation in said housing 28 (see Fig. 4). Said gear ring is formed with a shoulder 31 and is adapted to be held in place by an annular plate 32 secured to the bottom of said housing 28. Said gear 27 is formed with a downward hub extension 33, into which is threaded a stud 34 projecting upwardly from a backing disk 35 adapted to be disposed within the container to back up the seam during the seaming operation.

Said gear ring 29 has an inwardly extending flange 36, to which a chuck 37 is secured by means of screws 38, the lower edge of said chuck being shaped to clamp against the top of the cover member 13 to hold

the same firmly upon the can body during the seaming operation. It will thus be apparent that rotation of the shaft 22 in turn rotates the chuck 37 and the backing up disk 35, thereby rotating the can at a proper rate of speed with the seaming rollers in contact with the flanges to be folded in a double seam, as will hereinafter appear.

Referring now again to Figs. 1 and 2, the mechanism for supporting the can and presenting the same to the seaming mechanism will be described. A support plate 39 is adjustably and rotatably mounted upon a plunger 41, carried at the upper end of a vertical rod 42 slidably mounted in a bracket 43 extended outwardly from the column 15, said rod being slotted at the lower end thereof, as indicated at 44, and adapted to receive the forward end 45 of a lever 46, which is pivoted at 47 to a downward extension 48 of the bracket 43. The opposite end of said lever 46 is pivoted at 49 to an adjustable bracket 51 on a vertical rod 52 pivoted at its lower end at 53 to a foot lever 54, which is pivoted at its rear end to an upward standing lug 55 on the base 16. The forward end of said lever has a foot pedal 56 formed thereon and guides 57 are provided upon the base 16 intermediate the ends of said lever to hold the same in centered position. Said lever is normally held in raised position by means of a spring 58 secured at its lower end to the lever rearwardly of the connection 53 with the rod 52, the upper end of said spring engaging a hook 59 extending outwardly from the column 15. It will be apparent that depression of said lever against the tension of the spring 58 will lift the support plate 39 and raise the can to seaming position.

The cans may be positioned upon the support plate 39 by hand, or any preferred manner, and at this time have the bottom ends secured thereto and the covers 13 placed loosely thereon, see dotted position in Fig. 6 of part 116. The seaming mechanism at this time is retracted and the can is positioned or manipulated in such manner as to cause the disk 35 to enter the opening 14 and be arranged in the position shown in said Fig. 4. With the can parts clamped between the chuck 37 and the support plate 39, and the backing disk 35 arranged in contact with the cover and body at the seaming line, it will be apparent that rotation of said chuck and disk in unison will rotate the can body and support plate therewith and the seaming mechanism is then presented in proper relationship to cooperate with the rotating can to form the seam.

Said seaming mechanism, as shown, comprises a turret 61 (see Figs. 1, 3 and 4), which, in the present instance, carries two sets of seaming rollers, each set comprising 65 rollers for three different operations and

the sets being duplicated merely for mechanical convenience, it being understood that only one set of rollers operates upon a single can. The turret 61 is adapted to be moved horizontally to bring the same into seaming position and to be rotated to successively present the different operation rollers, in manner which will be presently described. Said turret and associated parts are carried by a sliding block 62, mounted upon a guideway 63 and adapted to be adjusted for cans of different diameter by means of a threaded rod 64 provided with a handle 65. A hand screw 66 is provided for vertical adjustment.

The turret 61 is mounted upon a vertical shaft 67 and comprises an upper part 68 and a lower part 69 between which second operation seaming rollers 71 are disposed, said rollers being mounted upon studs 72, held in place by set screws 73. Said shaft 67 extends through a hub portion 74 of a sliding frame 75, movable horizontally in guideways 76 in the block 62. Said shaft carries at its lower end a disk 77, which has an upward sleeve extension 78 upon which is loosely mounted a gear 79, having a ratchet connection with the top of said disk, said connection being provided by teeth 81 on the bottom of the gear and a spring-pressed dog 82 extending upwardly from the top of said disk 77, said dog being normally held extended by means of a spring 83 held within said disk by means of a plug screw 84.

The seaming mechanism just described is adapted to be advanced to operative position by means of a handle 85 (see Fig. 3), which is pivoted at 86 to the frame 75 and is of bell crank formation, one arm 87 thereof being pivotally connected at 88 to an arm 89, which is pivoted at 91 to the top of the block 62. By turning the handle 85 on the pivot 86, the distance between the points 86 and 91 is shortened or lengthened and the frame 75 and mechanism carried thereby shifted laterally, in manner which will be readily understood. One of the first operation rollers, indicated by the reference character 92 in Fig. 3, is first brought into contact with the seam parts of the can and performs an operation which will presently be described. Upon completion of the first operation, the frame 75 is retracted and again advanced to bring one of the second operation rollers 71 into operative position, the turret being rotated through an arc of 60°, or the distance between said roller, upon each backward sliding movement of said frame, the rotation being effected through engagement of the gear 79 with a rack 94 secured to the block 62. The teeth 81 and the ratchet dog 82 are formed in such manner that they are locked together during the backward sliding movement of the frame 75, said dog being adapted to slide over said teeth when the movement is in the opposite

125

130

direction, this being permitted by compression of the spring 83. Upon completion of the second operation, said frame 75 is again retracted and advanced to bring one of the 5 third operation rollers 93 into action, the turret 61 being rotated as hereinbefore described to present this roller. A centering button 95 is provided in the frame 75 and adapted to be held in appropriate depressions 96 in the shaft 67 to hold the latter in appropriate position, said button being under the tension of a spring 97 held in place by means of a screw 98 in said frame 75. It will be understood that the gear 79 is also 10 rotated upon the forward movement of said frame 75, but, by reason of the form of the ratchet teeth 81 and the spring mounting of the dog 82, the latter is depressed by and snaps over said teeth, so that the rotation 15 of said gear 79 is not imparted to the disk 77 or the turret 61.

The parts mounted upon the shaft 67 are held in assembled relationship by means of upper and lower washers 99 and 101, a nut 20 102 upon a top extension 103 of said shaft holding the washer 99 in place and a screw 104 being provided at the lower end of said shaft for retaining the washer 101.

Referring now particularly to Figs. 5 to 30 8, inclusive, the construction and operation of the seaming rollers will be described. The first operation seaming roller, shown in detail in Fig. 5 and diagrammatically in Fig. 6, comprises an upper section 105 and a lower section 106 upon which said upper section is slidably mounted, both said sections being rotatably mounted about a fixed stud 107 extending through the turret 61, which is provided with a suitable recess 108 35 to receive said roller parts and associated mechanism. The upper roller section 105 has relatively large central bores 109 and 111 to permit sliding movement of the same upon the section 106 and a block 112, under 40 the tension of a spring 113, which is provided in said recess 108 to normally hold said roller section 105 in its advanced position. When the first operation rollers are brought 45 into action, the body flange 114 is in horizontal position, as shown in Figs. 4 and 6, and the cover flange comprises a substantially horizontal portion 115 and a substantially vertical portion 116 shown in dotted lines in said Fig. 6. The roller section 105, 50 being in advance of the section 106, first comes into contact with a wall portion 117 on the cover and remains in this position while the turret 61 continues to advance, the lower roller section at this time advancing 55 from the dotted line position, indicated at 118 in the drawings, to the full line position, indicated at 119, and bending the flange portion 116 from the dotted line position to the full line position of Fig. 6. This action is 60 permitted by the spring mounting of said 65 upper roller section 105, the spring 113 being compressed during the advancing movement of the turret after said roller section has been brought into contact with the container cover. It will be understood that 70 during this operation, the can is firmly held between the support plate 41 and the chuck 37 and the inside of the seam is backed up by the disk 35, the can and said disk being rotated so that the entire flange 116 is acted 75 upon by said roller and brought to the hook formation shown in full lines in Fig. 6.

After the first operation has been completed, the frame 75 is retracted, in the manner previously explained, and during 80 the backward movement, the turret 61 is rotated and the seaming mechanism shifted to bring one of the second operation roller units into operative position, this unit being shown in Figs. 4 and 7 of the drawings. 85 Said unit comprises the roller 71 previously described and an auxiliary roller 121, which is mounted on a stud 122 in a sliding block 123 mounted in a guideway 124 in a fixed block 125. Said sliding block 123 is normally held in down, or retracted, position by means of a spring 126 disposed in said guideway and adapted to be compressed between the upper end 127 thereof and a pin 128 carried by said sliding block 123. The disk 77 90 carries rollers 129 at opposite sides thereof and as said disk is advanced, one of said rollers is brought into contact with the lower beveled end 131 of said block 123, the block being thus lifted and the roller 121 brought to 95 position to co-act with the roller 71 in bending the seam to the downwardly inclined position shown in Fig. 7. After the can has been sufficiently rotated to perform this second operation, the frame 75 is again retracted and the turret 61 rotated to again 100 shift the seaming mechanism and present one of the third operation rollers 93, which is diagrammatically shown in Fig. 8. This roller is provided with a central groove 132, 105 adapted to receive the partially formed seam, which latter, upon advancing movement of said roller, is bent downwardly against the can body, as shown in Fig. 8. Upon completion of this operation, the frame 110 75 is again retracted and the can, with the cover seamed thereto, may then be removed by lowering the support plate 39, the can being manually disengaged from the disk 35. Another can may then be positioned 115 and the cycle of operations repeated. By the last retraction of the seaming mechanism it is shifted the third time to bring the first operation roll of the second set opposite to the chuck and ready for the next can to 120 be closed.

It is thought that the invention and many of its attendant advantages will be understood from the foregoing description, and it will be apparent that various changes may 130

be made in the form, construction and arrangement of the parts without departing from the spirit and scope of the invention, or sacrificing all of its material advantages, the form hereinbefore described being merely a preferred embodiment thereof.

I claim:

1. A can closing machine, comprising a can support, means for clamping the can and cover to be united thereto to said support, and seaming mechanism having a plurality of sets of seaming rollers each set serving for the closing of a can movable into and out of operative relation with said can to perform successive seaming operations in forming a seam intermediate the ends of the can, the seaming mechanism and can having relative rotary movement, and means for rotating the sets of seaming rollers from one set to another set in one direction.

2. A can closing machine, comprising a can support, means for clamping the can and cover to be united thereto to said support, seaming mechanism movable into and out of operative relation with said can to perform successive seaming operations in forming a seam intermediate the ends of the can, means for rotating the can with the seaming mechanism in operative relation thereto and means for shifting the seaming mechanism when it is moved out of operation.

3. A can closing machine, comprising a can support, means for clamping the can and cover to be united thereto to said support, seaming mechanism movable into and out of operative relation with said can to perform successive seaming operations in forming a seam intermediate the ends of the can, means for shifting the seaming mechanism by its movement away from the can, means for rotating the can with the seaming mechanism in operative relation thereto, and means for backing up the seam during the seaming operations.

4. A can closing machine, comprising a can support, means for clamping the can and cover to be united thereto to said support, seaming mechanism movable into and out of operative relation with said can to perform successive seaming operations in forming a seam intermediate the ends of the can, means for shifting the seaming mechanism by its movement away from the can, means for rotating the can with the seaming mechanism in operative relation thereto, and means disposed within the can for backing up the seam during the seaming operations.

5. A can closing machine, comprising a can support, a rotatable chuck positioned above said support, said support and chuck being relatively movable to clamp a can and positioned end member therebetween, a backing member adapted to be inserted through an opening in the end member and ar-

ranged to back up the seam during the seaming operation, and seaming mechanism movable into and out of operative relation to the can to form a seam intermediate the ends thereof joining an end member to the can body and means for shifting the seaming mechanism by its movement away from the can.

6. A can closing machine, comprising a can support, a rotatable chuck positioned above said support, said support and chuck being relatively movable to clamp a can and positioned end member therebetween, a backing member adapted to be inserted through an opening in the end member and arranged to back up the seam during the seaming operation, said backing member being rotatable in unison with said chuck, gears for rotating said backing member and seaming mechanism movable into and out of operative relation to the can to form a seam intermediate the ends thereof joining an end member to the can body.

7. A can closing machine, comprising a can support, means for clamping an end member upon a can positioned upon said support, said end member and the can body having flanges adapted to be interfolded in a double seam intermediate the ends of the completed can, seaming mechanism including a turret having a plurality of different operation rollers mounted therein, manually operable means for moving said turret into and out of operative relation with the can, and mechanism for giving the turret a step by step rotation in one direction as it is withdrawn from the can.

8. A can closing machine, comprising a can support, means for clamping an end member upon a can positioned upon said support, said end member and the can body having flanges adapted to be interfolded in a double seam intermediate the ends of the completed can, seaming mechanism including a turret having a plurality of sets of different operation rollers mounted therein, each set serving for the closing of a can by successive operations, and manually operable means for moving said turret into and out of operative relation with the can, said last-mentioned means being adapted also to rotate said turret intermittently in one direction to successively present the different operation rollers for action upon the seam.

9. A can closing machine, comprising a can support, means for clamping an end member upon a can positioned upon said support, said end member and the can body having flanges adapted to be interfolded in a double seam intermediate the ends of the completed can, seaming mechanism including a turret having a plurality of different operation rollers mounted therein, manually operable means for moving said turret into and out of operative relation with the can,

and mechanism including a ratchet for automatically rotating said turret during the above-mentioned action thereof to successively present the different operation rollers to 5 position to be advanced into operative relation with the can.

10. A can closing machine, comprising a can support, means for clamping an end member upon a can positioned upon said 10 support, said end member and the can body having flanges adapted to be interfolded in a double seam intermediate the ends of the completed can, seaming mechanism including a pair of cooperating seaming rollers, one 15 thereof being slidably mounted and normally spring-held out of operative relation, said mechanism also including a laterally movable support for the other roller, and means movable with said support for moving said 20 first-mentioned roller into operative position.

11. A can closing machine, comprising a can support, means for clamping an end member upon a can positioned upon said 25 support, said end member and the can body having flanges adapted to be interfolded in a double seam intermediate the ends of the completed can, seaming mechanism movable into and out of operative re-

lation to the can and including a roller 30 comprising relatively movable parts, one of which is adapted to yield after being brought into contact with the can and during the continued advancing movement of the other.

12. A can closing machine, having in combination rotary can chucks for clamping between them the can and cover to be united, a plurality of seaming rolls and a carrier for said rolls which is movable toward and from the rotating can, and means for turning the roll carrier when it is operated by the movement of the carrier away from the can, to bring the seaming rolls in proper succession opposite the can so as to engage the latter when the carrier is again moved 45 toward the can.

13. A can closing machine having in combination, rotary chucks between which the parts of the can are clamped, a plurality of seaming rolls for operating successively 50 on the exterior of the can at the seam to be produced therein, a backing-up roller mounted within the can to operate on its inner surface opposite to said seaming rolls, and means for positively rotating said backing-up roller independently of the friction thereon of the can body.

JOHN M. HOTHERSALL.
